ULTRAHIGH FREQUENCY OSCILLATOR

John Evans, Collingswood, N. J., assignor to Radio Corporation of America, a corporation of Delaware

Application September 21, 1935, Serial No. 41,540

8 Claims. (Cl. 250—36)

My invention relates to ultrahigh frequency thermionic devices. More particularly, my invention is an ultrahigh frequency oscillator employing thermionic tubes in which the anodes are virtually at ground potential.

I am aware of numerous circuits for generating high frequency oscillations. Some of the proposed circuits will generate ultrahigh frequencies but the frequency is far from constant. Other circuits have been devised which generate oscillations of high and constant frequency but it is impossible to extend the range to frequencies exceeding fifty megacycles. Beyond these high frequencies the thermionic tube elements and the leads within the tubes assume electrical lengths of proportions which interfere with the higher frequency ranges.

One of the objects of my invention is the generation of oscillatory currents of ultrahigh frequencies.

Another object of my invention is to reduce the effect of the anode load on the input circuits of a thermionic tube.

A further object is to place the anodes of a pair of push-pull oscillator tubes at virtually ground potential.

Additional objects will appear in the following specification and claims.

Figure 1 is a schematic diagram of an ultrahigh frequency oscillator in which the anodes are at ground potential, and

Figure 2 is a diagram of an oscillator embodying one form of my invention.

It is well known to those skilled in the art that the characteristics of the input circuit of a triode are dependent on the load in its output circuit. Although this effect may not be of great importance at low frequencies, it is of extreme importance at high frequencies. By way of example, with one type of tube which has an input capacity of about 28 micromicrofarads with a zero plate circuit load, the effective input capacity will be approximately three times as great with an external load of 100,000 ohms. The output load may be inductive, capacitive or resistive and in each case the effective capacity or reactance of the input circuit will be effected. The input reactance may be effected in either a positive or negative sense.

Although these effects are not always deleterious, I have found that at ultrahigh frequencies the plate circuit load will limit the range of oscillation and ultimately limit the highest oscillatory frequency which can be reached. At frequencies of the order of 50 megacycles and lower,

depending mainly on the tube construction, the circuit of Figure 1 may be used.

In Figure 1 a pair of triode tubes 1—3 are connected in push-pull relation. The grids 5—7 are connected to the conductors 9—11 of a transmission line 13. A bridging member 15 is adjusted on the lines 9—11 until a quarter wave length characteristic is obtained. The center 17 of the bridge is grounded through a grid leak resistor 19. The cathodes 21—23 may be energized by any suitable source; for example batteries 25—27 or alternating current. In practice the capacity of the batteries or other source of cathode heating energy must be considered. Either filter networks or concentric lines should be employed between the batteries and the cathodes as will be described below. The batteries 25—27 in Fig. 1 are shown as directly connected to the cathodes 21, 23 merely for convenience of illustration.

Conductors 29—31 of a second transmission line 33 are connected to the cathodes 21—23. An adjustable bridging member 35 is connected to the transmission line at about a quarter wave length position at which the tuned grid, tuned cathode will cause oscillations. The center 37 of the cathode bridging member is grounded. The anodes 39—41 are connected together with the shortest possible leads. The center 43 of the leads between anodes is connected to ground through a suitable capacitor 45. The center is also connected to a radio frequency choke coil 47. The choke in turn is connected to the positive terminal of the anode current source 49. The negative terminal of the anode current supply 49 is grounded.

In the arrangement shown in Figure 1, if the length of the leads between the anodes is very short, the anodes will be maintained at ground potential for radio frequency currents because of the low reactance of the capacitor 45 which virtually grounds the anodes. Under favorable circumstances the anode output circuit will have substantially zero impedance and the effective input capacity will be relatively low and permit the generation of oscillatory currents of a frequency of the order of 50 megacycles. However, as the frequency is gradually increased, the leads between the anodes, and particularly the leads within the tube envelopes, will assume substantial effective reactances; i. e., substantial electrical length. The higher the frequency the greater will be the reactive component of the leads, or the more effective their length. This reactive component will act as a load on the out-

put circuit and effect the characteristics of the input circuit as explained above.

I propose to overcome this difficulty by arranging an output circuit which will have substantially no effect on the oscillation frequency and which will place the anodes at virtually ground potential at the highest frequencies. In Figure 2 a diagram of a circuit employing anodes at virtual ground potential is shown. A pair of triode thermionic tubes 51-52 are connected as a push-pull oscillator. The grids 53-55 are connected respectively to the conductors 57-59 of a transmission line 61. The line is adjusted to a quarter wave length by moving a bridging member 63 to the required position. The center 65 of the bridging member is connected to ground through the grid leak resistor 67.

The cathodes 69-71 are each energized by batteries 73-75 or other suitable source. Radio frequency choke coils 70, 72 are connected in each of the leads between the batteries 73, 75 and the cathodes 69-71. The batteries are each grounded. A pair of capacitors 74 and 76 are connected in series across each of the cathode leads. The junction of one pair of capacitors 74, 74 is connected to one of the conductors 77 of a transmission line 81. The junction of the other pair of capacitors 76, 76 is connected to the other conductor 79 of the transmission line. Although I have shown the filter network between the batteries and the cathodes, it is equally effective to make the transmission line 81 a pair of hollow conductors. One wire is connected within each conductor from the battery to the cathode and the hollow conductors are used for the return wires from each cathode to the battery. The cathode leads are by-passed by a suitable capacitor. In either type of connection, it is preferable to make the transmission lines straight, parallel and of equal length.

The proper length of the transmission line to sustain oscillations is found by moving the bridging member 83 whose center point 85 is grounded. The anodes 87-89 are connected to the conductors 91-93 of a transmission line 95. Across the end of the transmission line opposite the anodes is placed the bridging member 97. The center 99 of the bridging member 97 is grounded through a capacitor 101 whose reactance is low to the currents generated by the push-pull oscillator. The center 99 of the bridging member is also connected through a radio frequency choke 103 to the positive terminal of the anode current supply 105. The negative terminal of this supply is grounded.

If the bridging member 97 is carefully adjusted so that the transmission line is effectively a half wave length long, the anodes will be virtually at ground potential for the high frequency currents. The effect of the virtually grounded anodes is to make the output load of the anode circuit substantially zero and to remove the effects of this circuit on the input circuit. Using RCA type 852 tubes in push-pull relation with tuned input and tuned cathode circuits, I have been able to generate oscillations of the order of 500 megacycles, or 60 centimeters wave length.

Various obvious modifications within the scope of my invention will occur to those skilled in the art; by way of example, the grid and cathode circuits may be tuned with lumped inductance and capacity. I do not intend to limit my invention except as required by the prior art and the appended claims.

75. I claim:

1. In an ultrahigh frequency oscillator of the thermionic tube type in which the inductance of the anode electrode lead has sufficient reactance at said ultrahigh frequency to prevent grounding the anode electrode within the tube, a pair of thermionic tubes, each of said tubes including grid, cathode and anode electrodes, a ground connection, a grid circuit connected between said grid electrodes and said ground, a cathode circuit connected between said cathode electrodes and said ground, means for tuning said grid and cathode circuits with reference to the frequency of the oscillations to be produced, an anode circuit connected to said anode electrodes, means for grounding said anode circuit, and means for tuning said anode circuit to effectively a half wave length of said ultrahigh frequency oscillation whereby said grid and cathode circuits determine the oscillatory frequency of said oscillator and said anode circuit establishes an ultrahigh frequency ground potential on said anode electrodes within said envelope. 5 10 15 20

2. In an ultrahigh frequency oscillator of the thermionic tube type in which the anode lead offers a reactance at the frequency of operation 25 which prevents directly grounding the anode electrode within said tube, a pair of thermionic tubes, including within an evacuated envelope grid, cathode and anode electrodes, arranged to operate on opposite phases of oscillatory currents; 30 a ground connection, a grid circuit connected between said grid electrodes and ground, a cathode circuit connected between said cathode electrodes and ground, means for tuning said grid and cathode circuits to said frequency of operation, means 35 for impressing a positive direct current potential with respect to said cathodes on said anodes, and means for establishing an ultrahigh frequency ground potential on said anodes within said envelope. 40

3. In an ultrahigh frequency oscillator of the type in which the anode lead of a thermionic tube offers sufficient reactance to the frequency of operation to prevent directly grounding the anode within said tube, a pair of thermionic tubes 45 including within an evacuated envelope grid, cathode and anode electrodes and arranged to operate on opposite phases of their generated currents, a ground connection, a grid circuit connected between said grid electrodes and ground, a cathode circuit connected between said cathode electrodes and ground, means for tuning said grid and cathode circuits to said frequency of operation, means for impressing a positive direct current potential between said anode and cathode 50 electrodes, and means for establishing an ultrahigh frequency ground potential within said envelope on said anodes with respect to said ground connections. 55

4. In a push-pull ultrahigh frequency thermionic oscillator of the type in which the anode lead offers a reactance at the frequency of operation which prevents directly grounding the anode within said tube, a pair of thermionic tubes having input, anode and cathode electrodes; a ground connection, a transmission line of substantially one quarter wave length connected between said input electrodes and ground, a second transmission line of substantially a quarter wave length connected between said cathode electrodes and ground, and means for maintaining said anodes at points within said thermionic tubes at ground potential with respect to said ground connection for ultrahigh frequency cur- 60 65 70 75 80 85 90 95 98 99 100

rents and at positive direct current potential with respect to said cathode electrodes.

5. In a push-pull ultrahigh frequency thermionic oscillator of the type in which the anode lead offers a reactance at the frequency of operation which prevents directly grounding the anode within said tube, a pair of thermionic tubes having grid, anode and cathode electrodes, a ground connection, a transmission line of substantially 10 one quarter wave length connected between said grid electrodes and said ground, a second transmission line of substantially a quarter wave length connected between said cathode electrodes and said ground, and a third transmission line of substantially 15 a half wave length connected to said anode electrodes at one end and to ground at the other end and tune whereby the first mentioned end of said third transmission line is substantially at the potential of said ground connection with respect to high frequency currents, and a source of anode current supply, having a grounded negative terminal and a positive terminal connected to the second mentioned end of said third line.

20 6. In an ultrahigh frequency thermionic oscillator of the type in which the anode lead offers

a reactance at the frequency of operation which prevents directly grounding the anode within said tube, a thermionic tube having an evacuated envelope including grid, cathode and anode electrodes; a ground connection, a grid circuit connected between said grid electrodes and ground, a cathode circuit connected between said cathode electrodes and ground and an anode circuit connected between said anode electrodes and ground, means for tuning said grid and cathode circuits to 10 generate oscillations at said operating frequency, means for adjusting the effective electrical length of said anode circuit to a half wave length at said operating frequency whereby said anode electrode within said envelope will be at ground potential for said high frequency oscillations, a direct current supply and connections therefrom for positively biasing said anode electrode with respect to said cathode.

7. In a device of the character described in claim 4, means for adjusting the effective length of said transmission lines.

8. In a device of the character described in claim 5, means for adjusting the effective length of said transmission lines.

JOHN EVANS.
